BOWLING GLOVE

Ellery Donald Willard, Johnstown, N. Y.

Application November 17, 1942, Serial No. 465,867

1 Claim. (Cl. 2-21)

This invention relates to a hand covering, more particularly a protective glove to be used for bowling, especially on full sized bowling balls used on ten pin alleys.

The invention aims to provide a glove of a novel construction which will render full protection to the second and third fingers and thumb when gripping a bowling ball. A further aim provides for the elimination of all the covering over the back of the hand to permit a free grip and provide a bare hand feel of the ball.

Another feature of the invention aims to eliminate the usual bulky seams so that the fingers will fit into the holes of the bowling ball.

A still further object of the invention resides in the provision of a cloth back for the second and third fingers to permit such fingers to readily release the ball and imparting freedom and ventilation.

Other aims and advantages of the invention will appear in the specification, when considered in connection with the accompanying drawings, wherein:

Fig. 1 is a perspective view of the inside or palm side of the glove on a hand;

Fig. 2 is a perspective view of the back side of the glove on a hand;

Fig. 3 is a perspective view showing the gloved hand gripping a bowling ball;

Fig. 4 is a plan view of a palm and finger blank;

Fig. 5 is a plan view of a back finger blank; and

Fig. 6 is a plan view of a fourchette.

The glove is composed of a narrow palm portion 7, a thumb stall or sheath 8, a second finger stall or sheath 9, a third finger stall or sheath 10 and a wrist strap 11. Fig. 4 shows a blank 20 for the palm portion 7 and front portions 12 and 13 of the second and third finger sheaths, respectively, each having a side portion 12a and 13a, respectively. The cut out portion 14 is for the thumb 8 which is stitched to the peripheral edge of this opening by stitching 15, Figs. 1 and 2. The dotted lines 16 on the finger portions 12 and 13, Fig. 4, indicate the approximate fold lines for the finger sheaths.

The finger sheaths 9 and 10 are completed by sewing the fourchettes 17 and 18 and the back portions 19 and 20 connected to each other by back section 21, to the portions 12 and 13. The fourchette 17 is thus stitched to the back portion 19 and front portion 12 to form the third finger sheath 10 and fourchette 18 is stitched to the back portion 20 and front portion 13 to form the second finger sheath 9.

5 The strap is sewed by lines of stitches 22 to the bottom part of the palm portion 7 and this strap is provided with an adjustable buckle 23 provided with a snap fastener (not shown) or other suitable securing device.

The various parts of the glove may be made of any suitable materials such as leather, cloth, chamois, etc., but preferably the thumb sheath 8, palm portion 7, parts 12 and 13, fourchettes 17 and 18, and strap 11 are made of leather, whereas the blank 19, 20 and 21 comprising parts of the finger sheaths and the back section, is made of cloth or fabric.

10 To impart a pleasing and finished appearance to the glove, the edges 24 are turned over and stitched.

15 Fig. 3 illustrates how the gloved hand 25 grips a bowling ball 26 in that the sheathed thumb and second and third fingers project into the holes 27 in the ball 26. The bare index finger 28 and the bare fourth or little finger 29 rest on the ball. Most bowlers use the two fingers and the thumb for the holes in the ball, but it is also possible to use the glove with but one finger 9 or 10 in 20 its hole 27 and the thumb in its hole with perfect comfort and protection as well as control of the ball.

25 A glove constructed according to this invention presents many advantages which are obviously evident from the foregoing description and the drawings. The main advantage of the glove is that it affords complete protection to the second and third fingers and the thumb when gripping and releasing a bowling ball. The bare back portion of the hand permits a free grip, that is, the glove will allow the hand to tend to fold or grip thus giving a bare hand feel of the ball. The two finger sheaths 9 and 10 are so made that the usual bulky seams are eliminated, thereby permitting the fingers to properly fit into the holes of the bowling ball. Also, the cloth backs of the finger sheaths will permit the fingers to release the ball easily with perfect freedom and ventilation.

30 The one-piece construction of the palm and finger portions extending from the wrist to the tip of the fingers and forming two sides of the fingers with the fourchettes, eliminates seams and with the bound or turned edges, provides a perfectly reinforced and accurately fitting glove. The leather of the glove in contact with the bowling ball provides a sure grip and will prevent the ball from slipping out of the hand. Also, the leather in contact with the ball affords a better control of the ball.

35 40 45 50 55 The glove gives a better and uniform grip at a

times, prevents slipping, and gives the bowler better control of the ball. The easy grip with the glove does not tire the fingers and thumb. Also, the glove absorbs perspiration and it is very sanitary since it is not necessary to chalk the fingers or wipe the hands on public towels.

Obviously, the present invention is not restricted to the particular embodiment thereof herein shown and described.

What is claimed is:

A glove particularly for use with bowling balls, comprising a palm section having an opening for the thumb of the wearer; a thumb sheath seamed to the palm section around said opening; a front

and side portion for the second finger of the wearer; a front and side portion for the third finger of the wearer, said front and side portions being integral with each other and the front portions being integral with the palm section; a fourchette seamed to each front section; back finger sections for both front portions connected together by an integral back strip at the base of the fingers, each finger section being seamed to its front section and fourchette to form complete second and third finger sheaths; and means secured to the wrist end of the palm section to secure the glove on the hand of the wearer.

ELLERY DONALD WILLARD.
